United States Patent Office

Des. 179,958
Patented Mar. 26, 1957

179,958

COMBINATION BROILER AND OVEN OR THE LIKE

Clarence K. Vincent, Houston, Tex.

Application October 1, 1953, Serial No. 27,040

Term of patent 14 years

(Cl. D81—1)

Fig. 1

Fig. 2

Figure 1 is a side elevational view of a combination broiler and oven, or the like, showing my new design;

I claim:

The ornamental design for a combination broiler and oven, or the like, as shown.
